UNITED STATES PATENT OFFICE.

JOSEPH GLATZ, OF PHILADELPHIA, PENNSYLVANIA.

ELECTRIC FUSE-PLUG.

1,313,283.

Specification of Letters Patent.

Patented Aug. 19, 1919.

Application filed February 8, 1919. Serial No. 275,713.

To all whom it may concern:

Be it known that I, JOSEPH GLATZ, a citizen of the United States, residing in the city and county of Philadelphia, State of Pennsylvania, have invented a new and useful Electric Fuse-Plug, of which the following is a specification.

My invention consists of a novel construction of an electric fuse plug, wherein the number of parts is reduced to a minimum, certain parts heretofore employed having been eliminated in my invention, whereby I have produced a novel device which can be cheaply manufactured and assembled, is effective in operation, and is not likely to get out of order.

In carrying out my invention, I employ a body portion having therein a cavity or recess of a novel contour, which extends into said body preferably at an angle to the median or axial line thereof, and I locate in said cavity, a conducting clip and also a non-conductor of novel contour, between the lower portion of which is located a fuse wire, whose construction will hereinafter be more fully set forth.

One of the objects of my invention is to provide a socket having novel means for permitting the insertion and removal of the fuse metal, and for enabling the latter to make the necessary contact with the thread on the plug.

A further object of my invention is to provide in conjunction with an improved, renewable fuse, side channels in the plug affording means for permitting the ready and instantaneous escape of the gases generated by the blowing out of the fuse metal.

A further object of my invention is to collocate in a novel manner, a fuse of any conventional type with a threaded outer conducting shell permanently secured on the body of the plug and having a lip contacting with the fuse metal, in conjunction with a novel removable, taper, wedge-shaped non-conductor, which latter, together with the fuse metal, is properly held in assembled position by a novel removable clip of conducting material.

With these and other objects in view, the invention comprises certain novel constructions, combinations and arrangement of parts as will hereinafter more fully be described and claimed.

For the purpose of illustrating my invention, I have shown in the accompanying drawings one form thereof, which is at present preferred by me, since the same will be found in practice to give satisfactory and reliable results, although it is to be understood that the various instrumentalities of which my invention consists can be variously arranged and organized and that my invention is not limited to the precise arrangement and organization of these instrumentalities, as herein shown and described.

Figure 1 represents a side elevation, partly in section of an electric fuse plug embodying my invention, the section being taken on line 1—1, Fig. 2.

Fig. 2 represents a plan view of Fig. 1.

Fig. 3 represents a perspective view of the non-conducting wedge and conducting clip employed in detached position.

Similar numerals of reference indicate corresponding parts in the drawings.

1 designates my novel construction of electric fuse plug, the same comprising the body 2 of suitable non-conducting material, such as rubber or the like, having the upwardly projecting extension 3, which is engaged by the threaded shell 5, of brass, copper or similar conducting material. The shell 5 is caused to engage the extension 3 as indicated at 4, so that said shell cannot be readily removed from said extension. The top of said shell 5 is provided with the inwardly turned flange 6, which has a portion 7 formed with a downwardly deflected tongue or terminal 8, which is adapted to be bent downwardly or in an oblique angle against the wall 9 of the cavity or recess 10. This cavity 10 contains the fuse, non-conducting wedge and conducting clip to be hereinafter referred to and extends into the socket body at an angle to the axis thereof, and comprises the inclined wall 11, which extends at an angle downwardly into the body to the bottom or concavity 12, from which latter extends upwardly the diverging opposite wall 13, which merges into the wall 14 from which extends upwardly the inclined wall 15, which may be parallel to the wall 11 and merges into the wall 9. The cavity 10 has the parallel side walls 16 as will be seen from Fig. 2, which at the left hand terminate in the walls 17 and 18, the two latter forming the sides of an angular shaped channel, whose

bottom is formed by the wall 14, the function of said channel being to permit the ready upward escape of the gases, when a fuse blows out, as will be hereafter explained.

19 designates a clip or conductor of brass, or similar conducting material, whose top terminates in the laterally deflected contact point 20, which engages the top of the 10 wedge-shaped non-conductor or wedge 21. The lower portion of the clip 19 is bent as indicated at 22, and extends upwardly a short distance as indicated at 23.

The wedge-shaped non-conductor 21 has 15 the inclined walls 24 and 25 which converge downwardly and terminate at their bottom in the curved walls 26, there being a space between the wedge-shaped non-conductor 21, and the clip 19, the lower portion of which 20 space is occupied by the fuse 27, the latter having the short upwardly extending portion 28 and the longer upwardly extending member 29, which may extend to the top of the wedge 21, as seen in Fig. 1.

25 In order to enable the non-conducting wedge 21 and its adjuncts to be readily removed from the plug when desired, by the thumb and fingers, I form the downwardly inclined walls 30, which slope from the outer 30 portion of the socket body to about the dotted line 31, seen in Fig. 1, whereby the wedge 21 and its adjuncts can be readily grasped and pulled upwardly from the cavity 10, when desired.

35 It will thus be seen from the foregoing that my novel plug has a cavity 10 therein which extends at an angle to the median line or axis of the plug, and that the walls 11 and 13 of said cavity converge down- 40 wardly, while the walls 15 and 11 are parallel and the walls 16 are also parallel.

It will further be seen that the walls 24 and 25 of the non-conducting wedge 21 converge downwardly and that the clip 19 when 45 the parts are assembled is contiguous to the wall 11 of the cavity 10, the contact 20 engaging the top of the wedge 21 and the U-shaped bottom end of said clip surrounding the bottom of the wedge 21, and holding 50 the lower end of the fuse 27 in fixed position with respect to the bottom of the wedge 21.

It will further be apparent that by the wedging action of the non-conductor 21 with respect to the clip 19 and its adjuncts, all the 55 parts are firmly held in position, after being assembled.

The operation and manner of assembling the parts will be apparent to those skilled in the art. The lower end 27 of the fuse 29, 60 having been bent around the lower end of the wedge 21, the clip 19 is then slipped upon the wedge, and the fuse, wedge and clip are inserted into the position seen and properly retained by frictional contact.

65 The upper end of the fuse 29, forms a con-

tact with the threaded conducting shell through the medium of the down-turned lip or tongue 8, and in case the fuse blows out, the gases have a free exit upwardly through the side channels formed by the walls 17 70 and 18.

For convenience of manufacture, I form the walls 11 and 15, parallel by means of any suitable implement, but this is not essential, it being only necessary that the side channels be formed in any suitable manner for the egress of the gases, when a fuse blows out.

It will be apparent that by reason of the provision of the cavity 10 having the walls 80 9 and 11 inclined in the manner described, in conjunction with the employment of the non-conducting wedge 21 shaped substantially as described, that when the threaded shell 5 is screwed into position and pressure 85 is exerted upon the contact or terminal 20, the tendency will be to wedge the upper under surface of the fuse 29 tightly against the tongue, lip or contact point 8, thereby producing an effective electrical connection 90 between the fuse and the contacting outer threaded shell 5. It will be further apparent that by constructing and assembling the wedge 21, clip 19 and fuse 29 in the manner described, these three elements can be readily inserted and withdrawn from the cavity 10 as a unit.

It will now be apparent that I have devised a novel and useful construction of an electric fuse plug, which embodies the features of advantage enumerated as desirable in the statement of the invention of the above description, and while I have in the present instance, shown and described preferred embodiments thereof which will give 105 in practice satisfactory and reliable results, it is to be understood that the same is susceptible of modification in various particulars without departing from the spirit or scope of the invention or sacrificing any of 110 its advantages.

Having thus described my invention, what I claim as new and desire to secure by Letters Patent is:—

1. In a device of the character stated, a 115 plug having a cavity therein, a non-conducting wedge, a conducting clip and a fuse adapted to be inserted and withdrawn from said cavity as a unit, and side channels extending from said fuse upwardly at each side of said wedge for permitting the escape of gases created when a fuse blows out.

2. In a device of the character stated, a body having a cavity therein contained in an upward extension from said body, a 125 threaded shell of conducting material secured to said extension and having a downwardly turned lip engaging a wall of said cavity, a non-conducting wedge, a clip engaging the top and bottom of said wedge, 130

- and a fuse held between said clip and wedge and having its upper end contacting with the lip of said shell.
3. In a device of the character stated, a body having an extension provided with a cavity therein, inclined at an angle to the median line of said body, a non-conducting wedge having downwardly converging walls, a conducting clip having a deflected upper portion engaging the top of said wedge and a bent bottom portion engaging the bottom of said wedge, a fuse having its lower end held between said clip and wedge, a threaded casing engaging said extension, and means for forming a contact between the upper end of said fuse and said casing.
4. In a device of the character stated, a body having an extension provided with a threaded conducting shell, an inclined cavity in said extension, a portion of said shell having a lip deflected into said cavity, a wedge, clip and fuse adapted to be inserted into and withdrawn from said cavity as a unit, and side channels extending from said cavity upwardly at each side of said wedge to form passages for the escape of the gases created by a blown fuse.
5. In a device of the character stated, a plug having a cavity therein inclined at an angle to its median line, a non-conducting wedge, a conducting clip, and a fuse adapted to be inserted and withdrawn from the said cavity as a unit, and a threaded shell engaging said plug and having an integral tongue deflected into said cavity, and in contact with said fuse when the parts are assembled.
6. In a device of the character stated, a plug having a cavity therein extending at an angle to its median line, a non-conducting wedge, a conducting clip, and a fuse, adapted to be inserted and withdrawn from said cavity as a unit, the top of said wedge extending at a right angle to said median line, said channels extending from said fuse downwardly at each side for permitting the escape of gases when the fuse blows out, and inclined side walls at the top of said plug for permitting the wedge and its adjuncts to be readily grasped when it is desired to remove the same.

JOSEPH GLATZ.
